UNITED STATES PATENT OFFICE.

OLLIE A. GREEN, OF NEW YORK, N. Y.; KATE GREEN EXECUTRIX OF SAID OLLIE A. GREEN, DECEASED.

SCAFFOLD-HANGER.

1,126,986.

Specification of Letters Patent.

Patented Feb. 2, 1915.

Application filed December 17, 1913. Serial No. 807,195.

To all whom it may concern:

Be it known that I, OLLIE A. GREEN, a citizen of the United States, residing in the city of New York, borough of Bronx, county 5 of New York, and State of New York, have invented a certain new and useful Scaffold-Hanger, of which the following is a specification:

This invention is a scaffold hanger for use 10 in building construction, and the object of the invention is to produce a hanger which is simple in construction, easy to install, efficient in operation, and economical to manufacture.

15 Among the important features of the invention are the following: first, a plurality of scaffold hangers operable from a common source of power; second, selective mechanism whereby any one of said hangers may 20 be operated at will, independently of the others; third, means whereby the scaffold operating mechanism may be positioned within the building, at the same time, means being provided for suspending a scaffold 25 outside of the face of the wall thereof; fourth, controlling means positioned adjacent the scaffold for controlling the power medium; fifth, means for controlling the selective mechanism controllable from the 30 scaffold; sixth, improved mechanism for allowing freedom of rotation of the drums on which the fall ropes are wound; and, seventh, specific improvements in the scaffold operating mechanism whereby its construction 35 is simplified and its efficiency increased.

Features of the invention other than those specified will be apparent from the following description taken in connection with the accompanying drawings.

40 In the accompanying drawings I have illustrated one practical embodiment of the invention, but the construction shown therein is to be understood as illustrative, only, and not as defining the limits of the invention.

45 Figure 1 is a side elevation of a scaffold hanger embodying the present invention mounted on a building, a portion of the wall and structural work of which is illustrated 50 in cross section. Fig. 2 is a plan view of

the hanger shown in Fig. 1. Fig. 3 is a vertical longitudinal section through the frame which carries the cable operating mechanism. Fig. 4 is a transverse section on line 4-4 of Fig. 2. Fig. 5 is a detailed perspective of a dog which I employ to operatively connect the drums, on which the cables are wound, to the cable operating mechanism. 55

Referring to the drawings, A designates a pair of carrier beams preferably of channeled section, which beams are adapted to be positioned, in parallel relation, on a building so as to project out over the wall thereof, the rear ends of said beams being suitably anchored to the building, thus rendering the outer or projecting portions thereof capable of supporting the weight of a scaffold. 60

By my invention means are provided whereby the fall ropes for supporting the 70 weight of the scaffold may be hung from the anchored carrier beams, A, but operable from a point inside the face of the wall of the building. Thus the carrier beams, which form the body of the hanger, are only 75 called upon to sustain the weight of the scaffold, and not the additional weight of the cable operating mechanism, as was usual heretofore.

For convenience in handling the hanger, 80 i. e., moving it from place to place, I preferably mount the cable operating mechanism in a frame, and position said frame on or adjacent to the carrier beams, A.

Referring more particularly to Figs. 1, 85 3 and 4, the frame of the hanger is shown as composed of two parallel channeled beams, B, which are held in spaced relation by transverse ties, b. At a point intermediate the ends of the frame, and preferably about midway, a transverse shaft, C, is journaled in the frame and a pair of loose drums, D, D', are mounted for free rotation thereon. Mounted on the shaft, C, intermediate the drums, D, D', is a worm wheel, 90 E, which worm wheel has provided on either of its faces, pawls, e, e', adapted for engagement with ratchet wheels formed integral with the respective drums, D, D'. The drums, D, D', carry the cables, d, d', which 100

support the scaffold. The cable, d , which sustains the weight of that portion of the scaffold nearest the wall of the building, is wound around the drum, D, and from thence passes over a sheave, d^2 , mounted on a spindle, d^4 , carried by the carrier beams, A, and from thence said cable drops sheer to the inner edge of the scaffold, F. The cable, d' , which supports that portion of the scaffold most remote from the wall, passes from the drum, D', to the sheave, d^3 , mounted on a spindle, d^5 , near the outer ends of the carrier beams, from whence said cable passes directly to the outer edge of the scaffold.

15 Mounted longitudinally on the frame, A', is a shaft, G, which has affixed thereto a worm, g, positioned to mesh with worm wheel, E, the end of said shaft terminating in a beveled gear, H. This beveled gear 20 meshes with a pair of beveled pinions, I, I', loose on a shaft, j, journaled transversely in the frame. The shaft, j, is positioned in the same horizontal plane as the shaft, G, and the beveled pinions, I, I', thus engage 25 the beveled gear, H, at diametrically opposite points. It is through the shaft, j, that the cable operating mechanism is actuated, this shaft being adapted to be driven at a constant speed, and in a constant direction by means of any suitable power mechanism, e. g., the motor, X, illustrated.

In order that the power of the shaft, j, may be utilized to drive the beveled gear, H, suitable clutch mechanism is provided. 30 This mechanism is illustrated as embodying a sleeve, J, keyed, against rotation, to the shaft, j; but adapted for sliding movement thereon. At each end of the sleeve, J, are formed male clutch members, j' , j'' , 35 adapted to coöperate with the female clutch members, i , i^2 , formed integral with the respective beveled pinions, I, I'. Thus when the sleeve is shifted in one direction, the clutch members, j' , i^2 , will coöperate to 40 transmit rotation from the shaft, j', to the shaft, G, to wind the cables, d , d' , upon their respective drums, whereby the scaffold is raised. However, when the sleeve, J, is shifted the other way, the power will be 45 transmitted to the shaft, G, in the opposite direction, to unwind the cables from the drums and thus lower the scaffold.

For convenience in operating the clutch mechanism, just described, and particularly 50 with a view to allowing the controlling 55 gear from the scaffold, I provide the sleeve, J, with two fixed collars, j^3 , intermediate which is positioned the ends of a yoke, K, which is pivotedly mounted on the 60 supporting tie, b', fixed on the frame. Formed integral with the stem of the yoke, K, is a rocker arm, K', extending transversely of the frame, to the ends of which may be attached lines, k, k'. These lines

are preferably led to the outer ends of the 65 carrier beams, A, where they pass over sheaves, and from thence fall sheer to the scaffold. Manifestly, a workman on the scaffold may, by pulling on either of the lines, k, k', raise or lower the scaffold at 70 will. I have hereinbefore stated that the frame, A', is preferably made separate from the carrier beams, A', for the purpose of allowing the hanger to be moved about in parts of comparatively minimum weight in 75 themselves. In the practical use of the hanger, however, I find it advisable, in view of the fact that the carrier beams are anchored in place to detachably mount the frame, A', on said carrier beams, and thereby preclude the necessity of a double anchoring to the building. Consequently, the frame, A', is adapted to be positioned on the carrier beams, A, at that portion thereof inside the building wall, and the frame is 80 detachably secured to said beams by means of straps, l, which are bolted at their respective ends to the frame and to the carrier beam. The parts may thus be readily detached by withdrawing the bolts in either 85 of said members.

I have set forth in the foregoing description the construction of a single hanger, the shaft, j, of which can be driven from any desired source of power. It is generally 90 necessary, however, to employ two or more hangers for a single scaffold and, by my invention the operating mechanism of these hangers may all be made operable from a common source of power by connecting the 100 various shafts, j, of the respective hangers by shaft sections, M, in a suitable coupling, m. When this is done it will be manifest that when one of said shaft sections or the shaft, j, of any one of the hangers is operated 105 on through the belt, N, and pulleys, n, n', by the power medium, X, the operating mechanism of all of the hangers may be actuated simultaneously. Moreover, the shaft may extend entirely around the building, bevelled gears being provided at the corners, and all of the scaffolds on the building may be actuated by a single motor or engine. In such a case the entire shafting would be 110 driven simultaneously and in synchronism with the power medium, and when a workman on a scaffold desires to raise or lower the same, he may do so by simply actuating the selective mechanism, hereinbefore described, for utilizing the power in the shafting for the purpose of operating his scaffold as desired. It is desirable, however, that in view of the fact that the scaffold is only moved occasionally, to provide means to make the source of energy, X, controllable from the scaffold, so that the power medium need operate only at such time as it is desired to shift the scaffold. I have, 115 120 125

therefore, shown the electrical circuit, α , which operates the power medium, controllable from the scaffold, the switch, α' , being illustrated for this purpose. If a 5 number of scaffolds are operatively connected to a single power medium, lines of wiring would be carried to each of the scaffolds so that said power medium can be rendered operable from each and every 10 scaffold.

It will be manifest from the foregoing description that the scaffold hanger of the present invention is extremely simple, yet, of highly efficient construction, and the fact 15 that all of the cable operating mechanism is positioned inside of the face of the wall of the building, obviates the great strain on the small leverage prevalent in hangers embodying cable operating mechanism, 20 mounted in that portion of the frame which projects out beyond the building wall. It is thus possible to make my hanger of much lighter material, and yet obtain increased strength. Moreover, the fact that the cable 25 operating mechanism is compactly mounted in a small frame, greatly facilitates the moving of the hanger from one position to another, since when dismantled, the parts are compact and light as compared to prior devices 30 in this art. I have found it possible, because of the automatic control and lightness of component parts, to change the point of suspension of a scaffold on a building from a lower to higher story, while the 35 workmen are engaged on the scaffold, and so smoothly can the operation be performed as to be hardly noticeable. When thus done, the required number of extra hangers positioned on the higher story, and the fall 40 ropes thereof allowed to run out until their ends can be attached to the cross cleats of the scaffold. The motive devices are then set into operation to tighten the cables and relieve the strain on the cables of the 45 hangers, which theretofore sustained the weight of the scaffold from a lower altitude. When this has been accomplished, said lower hangers may be dismantled and the scaffold left suspended by the uppermost 50 hangers.

As shown more particularly in Fig. 3, the drums, D, D', are operatively connected to the worm wheel, E, by means of dogs or pawls, e , e' , which I preferably lock in engagement with the ratchet surface on the drums, by means of withdrawable pins, e^a . Thus in the rigging of the scaffold, the pins e^a , may be withdrawn, and the dogs thrown back so as to allow the cables to run free. 55 thus obviating the necessity and precluding lost time which would be occupied in operating the power mechanism to unwind the cables to the desired extent. However, when the cables have run out sufficiently,

the dogs are again thrown into position and locked by the pins, e^a , so that all chance of accident is precluded.

The embodiment of the invention which I have chosen to describe, is well adapted for heavy work, but I have found that for 70 light work a hanger embodying two carrier beams are unnecessary, and a hanger embodying a single beam may be employed in their stead, the sheaves, b^2 , b^3 , being suitably mounted thereon.

It will be understood that the invention is not restricted to the entire mechanism shown, as certain parts thereof may be used separately or in combination with other types of scaffold mechanism. It will be further understood that, the precise location of the scaffold operating mechanism is not vital, and, while I have shown it as located in the preferred position, it may be positioned otherwise.

Having thus fully described the invention, what I claim as new and desire to secure by Letters Patent is:

1. A scaffolding and platform raising means embodying, in combination, anchoring means adapted to be secured to a building, one or more platforms suspended from said anchoring means at a plurality of points, means for suspending said platforms, separate drums controlling severally the suspending means, a common power shaft, and means connecting each of the drums with the common power shaft, said connecting means embodying mechanism for transmitting rotation to said drums 100 either in the same direction, as, or in reverse direction to, the direction of rotation of the power shaft.

2. A scaffolding and platform raising means embodying, in combination, anchoring means adapted to be secured to a building, one or more platforms suspended from said anchoring means at a plurality of points, means for suspending said platforms, separate drums controlling severally 110 the suspending means, a common power shaft, and means connecting each of the drums with the common power shaft, said connecting means embodying mechanism controllable from the platform for transmitting rotation to said drums either in the same direction as, or in reverse direction to, the direction of rotation of the power shaft.

3. A scaffolding and platform raising means embodying, in combination, anchoring means adapted to be secured to a building, one or more platforms suspended from said anchoring means at a plurality of points, means for suspending said platforms, separate drums controlling severally 125 the suspending means, a common power shaft, means connecting each of the drums with the common power shaft, said con-

necting means embodying mechanism controllable from the platform for transmitting rotation to said drums either in the same direction as, or in reverse direction to, the direction of rotation of the power shaft, and means controllable from the platform for driving the common power shaft in a constant direction.

In testimony whereof I have signed my name to this specification in the presence of 10 two subscribing witnesses.
